U.S. Cl. D14—30

FIG. 1.

FIG. 2.

FIG. 3.

FIG. 4.

FIGURE 1 is a side elevational view of a vehicle wheel, showing my new design;

FIGURE 2 is a cross-sectional view thereof taken on line 2—2 of FIGURE 1;

FIGURE 3 is a cross-sectional view thereof taken on line 3—3 of FIGURE 2, illustrating the cross-section of the outer portion of a spoke; and

FIGURE 4 is a cross-sectional view thereof taken on line 4—4 of FIGURE 2, illustrating the inner portion of a spoke near the hub portion.

The side opposite that shown in FIGURE 1 is a mirror image thereof.

The tire shown in broken lines in FIGURE 1 is included for illustrative purposes only.

This application is a continuation of my co-pending application, Ser. No. D. 6,441, filed Mar. 30, 1967, now abandoned.

I claim:

The ornamental design for a vehicle wheel, as shown and described.
